STAIRWAY POST AND BRACKET COMBINATION

Arthur L. Lang, 4021 Airport Way S., Seattle, Wash.

Filed Apr. 20, 1964, Ser. No. 79,596

Term of patent 14 years

(Cl. D13—7)

FIG. 1 is a perspective view of a stairway post and bracket combination embodying my new design.

FIG. 2 is a side elevational view of the stairway post and bracket.

FIG. 3 is a front elevational view of the stairway post and bracket.

FIG. 4 is a back elevational view of the bracket and the upper end of the post.

The broken lines on the drawing are disclosed for illustrative purposes only.

I claim:

The ornamental design for a stairway post and bracket combination, as shown and described.
